UNITED STATES PATENT OFFICE.

LOUIS HALK, OF HACKENSACK, NEW JERSEY, ASSIGNOR TO NORTHAM WARREN CORPORATION, OF NEW YORK, N. Y., A CORPORATION OF NEW YORK.

TOILET KIT.

Application filed March 15, 1928. Serial No. 261,754.

My invention relates to a new and improved toilet kit.

One of the objects of my invention is to provide a toilet kit which shall be useful for 5 travellers and which can be arranged upon the top of a dressing table or the like with the various bottles, jars, etc. of toilet preparations in visible and accessible positions.

Another object of my invention is to provide a device of this kind which can be readily cleaned or polished.

Other objects of my invention will be set forth in the following description and drawings which illustrate a preferred embodiment 15 thereof, it being understood that the above general statement of the objects of my invention is intended merely to generally explain the same and not to limit it in any manner.

Fig. 1 is a perspective view showing the 20 device in the operative position.

Fig. 2 is a lateral central sectional view showing the device in the closed position.

Fig. 3 is a view similar to Fig. 2 but showing the device in the open position.

Fig. 4 is a perspective view showing the 25 top tray of the device.

The device comprises a box 10 of any suitable shape having a cover 11 hingedly connected thereto. A tray 13 is adapted to rest 30 in the top of the body 10, the bottom of said tray resting upon any suitable means provided in the body of the box so as to form a lower compartment 19. The device is provided with any suitable lock and with a hand strap 35 20. The tray 13 is provided with a holder portion 15 having a downwardly directed flange 18, which rests upon the bottom of the tray 13. This holder portion 15 is connected to the rear of the tray 13 by means of a hinge 40 17. The holder portion 15 has the top thereof provided with a series of openings 16, in which a series of bottles or jars may be located, as shown in Fig. 1, so as to hold these bottles or jars ready for use, in such position 45 that they are readily visible and accessible.

The front wall of the tray 13 is provided 50 with resilient latch arms 14 which have downwardly bent rear ends, which bear against the flange 18 of the holder portion 15, so that this holder portion 15 is firmly held in the operative position illustrated in Fig. 4 for example.

However, and as shown in Fig. 3, said holder portion 15 can be swung away from the bottom of the tray in order to clean or polish the same. The tray 13 is made of any suitable metal which can be stamped or otherwise formed into shape.

The bottles of toilet preparations, which may be manicure preparations or the like can be placed in the compartment 19 or in the 60 open part of the tray 13, when it is desired to transport the box 10.

While I have described the device in the description and claims as being held in the horizontal position shown in Fig. 1, it is obvious 65 that the action of the device is substantially independent of said horizontal position.

I have shown a preferred embodiment of my invention, but it is clear that numerous 70 changes and omissions could be made without departing from its spirit.

I claim:

1. For use in a toilet kit, a tray having a bottom portion and a front wall and a rear 75 wall, a holding portion having an angular shape and provided with a horizontal wall having a depending flange which is adapted to rest upon the bottom of the tray, said horizontal portion being hingedly connected to the rear wall of the tray, said horizontal portion being provided with perforations adapted to hold containers of toilet preparations in position, and resilient latch means connected to the tray and adapted to bear against the said depending flange to maintain the said holding portion in operative position.

2. For use in a toilet kit, a tray having a holder portion provided with a vertical flange adapted to rest upon the bottom of the tray, 90 the top of said holder portion having means adapted to hold bottles or the like, and resilient latch means connected to the said tray bearing against said vertical flange and adapted to maintain the said holder portion 95 in operative position.

3. For use in a toilet kit, a tray having a bottom and a front wall and a rear wall, a holding portion hingedly connected to said rear wall, said holding portion being provided with a depending flange at the front thereof, and resilient latch means connected 100

to the front wall of the tray and bearing against said flange to maintain the said holding portion in operative position, said holding portion being adapted to maintain containers of toilet preparations in position.

4. For use in a toilet kit, a tray having a bottom and a front wall and a rear wall, a

holding portion having a series of perforations therein and being hingedly connected to said rear wall and resilient means connected to the toilet kit by which said holding portion can be held in operative position.

In testimony whereof I affix my signature.

LOUIS HALK.
